UNITED STATES PATENT OFFICE

WILLIAM W. ODELL, OF PITTSBURGH, PENNSYLVANIA, ASSIGNOR TO GLENN W. TRAER, JR., OF MINNEAPOLIS, MINNESOTA

PROCESS OF CARBONIZING AND DISTILLING CARBONACEOUS MATERIALS SUCH AS LIGNITE, COAL, WOOD, PEAT, AND SIMILAR MATERIALS

Application filed November 29, 1922, Serial No. 604,118. Renewed July 24, 1925.

This invention relates to the method of carbonizing or distilling materials by a continuous process wherein the materials are caused to pass through a hot zone—fire zone—in an opposite direction to the path of the gaseous products of combustion, which latter pass directly through the materials in process.

The objects of this invention are:

- 10 1. To render the carbonizing process cheaper,
2. To increase the capacity for a given size installation,
3. To render the process simple of operation,
- 15 4. To afford an easy means of discharging the carbonized product,
5. To afford a cheap means of cooling and quenching the carbonized product,
- 20 6. To provide a means of burning some of the gas liberated, in contact with the material in process, so as to economize fuel and hasten the carbonization,
7. To provide a means for transferring 25 heat from the hottest particles from carbonization to those less hot, after passing through the hot zones,
8. To provide a means for recovering some of the gas resulting from and during processing,
- 30 9. To provide a means for maintaining the mass of material in a loose rather than compact condition during processing and for promoting a mixing of the particles,
- 35 10. To process raw green lignite and the like in one step without previous drying.

In carbonizing coal, lignite, and the like, it has been the practice to burn gas in heating flues and utilize only the heat which passes through a wall of refractory material; the slow rate of heating occasioned by the use of these walls retards the process and makes it more costly, not only from a fuel consumption standpoint, but because of the costliness of the apparatus and necessary appurtenances.

In my process, I create a condition of combustion within the mass of the material in process, conducting the material in one direction through the hot zone and conducting the

gases of combustion in the opposite direction through the material, passing same out through the incoming cooler material. The hot zone is limited to a definite area, and the material is caused to pass through it so quickly that only a very small percentage of the fixed carbon is consumed in processing. 55

In the drawings:

Figure 1 is a front vertical sectional view showing one form of the carbonizer, in which 60 internal fuel baffles are formed integral with the tuyères which supply the air blast;

Figure 2 is a side elevation of the same type of carbonizer;

Figure 3 is a side vertical sectional view 65 of the same;

Figure 4 is a view partly in front vertical section and partly in front elevation showing a modified form of carbonizer having separate air ducts for supplying air from without 70 the fuel mass, and

Figure 5 is a side elevation of the upper portion of the carbonizer, shown in Figure 4.

In Figure 1, A is the oven wall, B is the mass of material in process, C and D are 75 the upper and lower tuyères, E is a gas off-take and baffle, F is a zig-zag discharge from the oven proper, G shows the inlets for steam or water for quenching, H is the revolving paddle mechanism by means of which the 80 carbonized material is removed from the oven, I is the opening in the wall above base plate J, so adjusted that by the natural angle of repose of the material treated the latter automatically feeds onto H. K is a foundation and L the I-beam supports for the oven proper. 85

At M and N are shown a narrowing in the oven, at and just above the hot zone; O and P are the zones of slow travel of the carbonizing materials. Q is the upper level or surface of the fuel in the oven, and R is the cooler for carbonized material, in which the zig-zag discharge is retained. 90

In Figures 4 and 5 is shown another apparatus in which I have been able to successfully carbonize materials by means of the same principles and process; the chief difference being that here air is admitted from openings in the outer wall instead of from 95 100

the middle and from within the fuel mass. The lettering in capitals refers to the same features in all of the figures. In these figures *a* and *b* are baffles controlling the course of the fuel downwards, *c* and *d* are the upper and lower sets of air channels feeding air to the fuel through ducts *e* and *f*.

In Figure 5 is shown a portion of the oven proper in side elevation, and portrays the means of supplying air to the material in process. The ports *e* and *f* are shown open; these are plugged on the outside to prevent escape of air when the oven is in operation.

In operating according to my process and 15 using the apparatus shown in Figure 1, I proceed as follows:

Fill the carbonizer (oven) with crushed or small sized fuel up to the first tuyère, start a fire at this level by igniting some 20 wood or other combustible, and add more fuel and start the air blast through the lower tuyère. Now add more fuel and repeat the ignition process at the upper tuyère, admitting air through the latter, and build 25 the fuel up to the desired level. Now start the discharge paddle drum *H* and replenish the fuel at frequent intervals by charging it into the open top of the oven so as to maintain a fairly uniform fuel level. The fuel passes 30 down through the hot zone and is carbonized, and the gases evolved during the process pass up through the fuel bed *B* and are in part burned within the fuel bed; the remainder is burned at the fuel surface *Q*. The air blast 35 through the tuyères is maintained throughout the operation. I find that with a given quantity of air blast through the tuyères *C* and *D*, the degree of carbonization is controlled by the velocity of travel of the fuel 40 (the quantity of material put through the process per unit of time)—and that for a given rate of fuel input, the degree of carbonization is dependent on the quantity of air injected at *C* and *D*. The carbonization is 45 more complete as the rate of travel of the fuel is decreased and as the quantity of air injected at *C* and *D* is increased, and vice versa. At no time is the fuel discharged faster than the state of ignition can be maintained at the tuyères.

When lignite is passed through the apparatus, the resulting residue will be a partly dried or thoroughly dry (water free) lignite, or a carbonized product containing volatile matter ranging from that of the thoroughly dried lignite to almost zero, accordingly as the rate of discharge is fast or slow. Partly dried peat blocks have been successfully carbonized in this manner, and 55 likewise wood and mixed fuels have been successfully treated thus.

Attempts have been made to utilize the producer gas generating principles in carbonizing materials, by passing the fuel rapidly through the producer, and such attempts

have not been successful, because the percentage of fuel consumed was high and the carbonization uneven. I have found by experiment with large size apparatus that in order to carbonize with a small consumption of fixed carbon, utilizing largely the gas evolved to generate the heat required, it is necessary that the fuel must pass through the hot zone where air is admitted, very rapidly. This I believe is to be new, and is a feature of my process and of the oven which provides the means. When the fuel moves slowly past the tuyères, considerable fixed carbon is always burned. I have carbonized lignite in the oven shown in Figure 1 with a fixed carbon consumption, during processing, of less than five per cent of the original lignite. I have found further that passing fuel containing a high percentage of moisture so rapidly through a single hot zone will not produce a well carbonized product. In other words, passing the fuel rapidly through at least two hot zones in succession (preferably one above the other as shown in Figures 1, 3 and 4), with a slower rate of travel between these zones wherein the particles in process change position with respect to each other, the hotter giving up heat to the cooler, produces a more uniform product, and results in a decrease in the percentage 95 of fixed carbon consumed. This I believe to be a new feature in carbonizing processes.

Since gas will burn preferentially to carbon when air is admitted in the presence of both at the temperature prevailing, I am 100 enabled to burn considerable of this gas in the upper combustion zones (gas which is chiefly liberated below). A further advantage gained by a rapid travel of the fuel through the hot zones is that the reaction $\text{CO}_2 + \text{C} = 2\text{CO}$, which takes place rapidly only at high temperatures, does not take place to the same extent that it otherwise would, thus again reducing the fixed carbon consumption.

Now since it is difficult to heat a mass of fuel of any appreciable thickness by air blasting—that fuel nearest the air supply always becoming intensely heated first—I have found it necessary to carbonize by supplying the heat to thin layers at a time, and accordingly have used this as a means of producing a high velocity of travel of the fuel in the hot zones; that is, by placing the tuyères in the narrow portions of the oven. This combination I believe to be new and novel.

In the oven as shown in Figure 1, the tuyères *C* and *D* are so placed that they act as baffles which permit of a certain amount of mixing of the particles after they pass and in passing the tuyères. A means is thus provided for the hottest particles to come into contact with the cooler ones and give up some of their sensible heat to the latter; the fuel mass is considerably larger at these locations, *O* and 125

P, and the rate of linear travel is slower, thus allowing sufficient time for heat transfer and completion of carbonization. Considerable gas is evolved during this heat transfer in the widened portions of the oven O and P (below tuyères), and since it cannot escape elsewhere, it is forced upwards and reaches a maximum velocity in the restricted portions of the oven, M and N, adjacent the tuyères, more particularly the upper one, M. Now this is a particularly desirable feature, since it is decidedly preferable to burn gas rather than burn carbon, and to use more air through the upper tuyère. There is an excess of gas produced when carbonizing some materials such as lignite, peat, coal, etc. and I prefer to burn some of this at the surface of the fuel bed, as at Q, Figure 1, for it is an aid in carbonizing. I have provided a means for withdrawing some of the gas through the pipe shown at E, Figure 1. This pipe has holes in its under side and conducts said gas from below the lower tuyère out of the oven. The heating value of the gas at this level when carbonizing lignite or coal is 180 to 240 B. t. u. If a large amount of gas is removed, producer gas is generated and the heating value of the total gas removed will depend on how much producer gas is made. The producer gas so made has a heating value of 140 B. t. u. per cubic foot. When just sufficient gas is withdrawn to operate the machinery for supplying the oven with air and power, its heating value is approximately 200 B. t. u. per cubic foot. With peat it is slightly higher than this.

I have found that the quantity of steam or water required for quenching the carbonized product is very much less than the calculated amount, indicating carbonization by heat transfer between particles in the oven at O and P. Now this heat transfer process aids materially in the cooling and quenching of the finished product, which is completely cooled by admitting exhaust steam through the pipes G, Figure 1. Water may be used in place of steam, but steam is preferable since a slight excess of water impedes the flow of residue and alters the angle of repose of the material between I and H of Figure 1. The residue (carbonized product) is cooled, it will be noted, in a mixed atmosphere of gas and steam in which there is no free oxygen; this apparently is a big advantage, for the product discharged, even though warm, does not take fire spontaneously in the air, which is not the case when some of said carbonized materials are quenched with water in the air.

The operation of this oven is automatic when fuel is supplied and the residue removed, and hence the labor cost for operating is low. There are no complicated flue settings or other complications in the design of the oven which require specialists for the latter's

construction. This oven is "get-at-able," and can be readily repaired when occasion requires it. The first cost obviously is relatively low. It can be started and shut down frequently without damage, which is not true of ovens with complicated flue settings. I have completely carbonized as much as 20 tons of lignite per 24 hours in this oven (inside oven dimensions being: 6 feet long and 3 feet wide in the widest portion), the lignite charged contained 30 per cent moisture and was crushed to sizes less than 2 inches in diameter. The air pressure used to obtain this capacity was less than two inches of water by a water manometer. The carbonized product, amounting to slightly more than 40 per cent of the original lignite was suitable for briquetting, or for burning as such.

The means of discharge, which I believe to be new, consists of a rotating drum with radial blades as shown in Figures 1, 2, and 4 at H, upon which the cooled carbonized product flows, through an opening I in the cooler, because of its tendency to assume a rather definite angle of repose. The quantity removed per unit of time depending on the speed of the rotating drum. Advantages claimed are that the discharge mechanism is always in sight, does not become overheated, can be repaired readily, and its operation is visible.

The operation of the oven shown in Figures 4 and 5 is the same. Here a and b are baffles, but are not also tuyères, as are the baffles in Figure 1 (C and D).

The pipe E shown in all the figures is not only a gas offtake, but it also takes some of the weight off of the zigzag part of the cooler, and thus leaves the residue therein in a looser state, and thus avoids jamming.

I do not limit myself to the use of air for promoting combustion in this process, for high temperature combustion gases with some air is just as satisfactory.

Having thus described my invention what I claim as new and desire to secure by Letters-Patent, is:

1. A process for carbonizing and distilling solid carbonaceous material in an oven, which consists in introducing the material to be treated, raising its temperature sufficiently to undergo combustion when treated with oxygen-carrying gas, passing the material substantially continuously in a downward direction and alternately causing contraction and expansion of the same, dividing the charge into streams during the contraction, causing the divided streams to then be brought together and allowed to expand, and maintaining a high temperature during constriction and division of the charge.

2. A process for carbonizing and distilling solid carbonaceous material in an oven, which consists in introducing the material to be treated, raising its temperature sufficiently to

undergo combustion when treated with oxygen-carrying gas, passing the material downwardly, and alternately causing it to expand and contract, dividing the material into streams at points of contraction, to increase the velocity at such points, injecting an oxygen-carrying gas to maintain the material at a higher temperature when traveling at this higher velocity, causing a part of the gas evolved to pass through the material in an upward direction and to be burned at the upper surface of the material, and maintaining the material in a loose state.

3. A process for carbonizing and distilling solid carbonaceous material in an oven, which consists in introducing the material to be treated, raising its temperature sufficiently to undergo combustion when treated with oxygen-carrying gas, in causing a charge of material to move continuously downwardly, then constricting and dividing the charge to substantially increase its rate of flow, then causing said charge to expand to reduce its velocity, and introducing air during constriction and division.

4. A process for carbonizing and distilling solid carbonaceous material in an oven which consists in introducing the material to be treated, raising its temperature sufficiently to undergo combustion when treated with an oxygen-carrying gas, causing the material to move through successive alternate combustion and heat-equalizing zones, passing the material in relatively restricted streams and at relative high velocity through said combustion zones, causing the streams to unite and travel in a single stream and at a relatively lower velocity through the heat-equalizing zones, introducing an oxygen-carrying gas into the material at the combustion zones.

5. In a process as defined in claim 4, the step which consists in passing the materials undergoing carbonization through the combustion zones at a velocity too great for their complete combustion but slow enough to maintain partial combustion sufficient to raise the temperature of said combustion zones substantially above the temperature of the heat-equalizing zones.

6. In a process as defined in claim 4, the step consisting in passing the gaseous products resulting from partial combustion of the materials undergoing a carbonization in a direction substantially counter to the flow of said materials.

7. In a process as defined in claim 4, the step which consists in causing part of the gases evolved during carbonization below the combustion zones to pass upwardly through said zones wherein they are in part burned by means of said oxygen-carrying gas.

8. In a process as defined in claim 4, the step which consists in causing part of the gases evolved during carbonization to pass through the carbonaceous materials in an

upward direction, and in part burning said gas in contact with said material by means of the outer air at the upper surface of the material.

9. A process for carbonizing and distilling solid carbonaceous material in an oven which consists in introducing the material to be treated, raising its temperature sufficiently to undergo combustion when treated with an oxygen-carrying gas, causing the material to move through successive alternate combustion and heat-equalizing zones, in such manner that the gases evolved in a lower combustion zone will pass to an upper combustion zone, and supplying an oxygen-carrying gas to the upper combustion zone so as to cause the burning of said gases thereat with a material reduction in the consumption of the fixed carbon of the material, and withdrawing the solid carbonized combustible residue.

10. A process for carbonizing and distilling solid carbonaceous material in an oven which consists in introducing the material to be treated, raising its temperature sufficiently to undergo combustion when treated with an oxygen-carrying gas, causing the material to move through a series of hot zones in which active combustion is maintained by supplying oxygen-carrying gas separately to each of said zones, conducting said material through said zones in substantially parallel and relatively restricted streams and at a velocity too great for its complete combustion, and then withdrawing the solid carbonized combustible residue.

11. A process for carbonizing and distilling solid carbonaceous material in an oven which consists in introducing the material to be treated, raising its temperature sufficiently to undergo combustion when treated with an oxygen-carrying gas, causing the material to move through alternate combustion and heat-equalizing zones, maintaining combustion in said combustion zones by supplying thereto an oxygen-carrying gas conducting said material through the combustion zones in substantially parallel streams and at a velocity too great for its complete combustion, and through the heat-equalizing zone in substantially a single conjoint stream at less velocity, and withdrawing the solid carbonized combustible residue.

12. A process for carbonizing and distilling solid carbonaceous material in an oven which consists in introducing the material to be treated, raising its temperature sufficiently to undergo combustion when treated with an oxygen-carrying gas, causing the material to move through successive hot zones in restricted streams, and at a relatively high velocity maintaining combustion at each hot zone by introducing an oxygen-carrier thereat, causing the gaseous combustion products to pass substantially counter to the path of the mate-

rial from the hot zones, conducting the material from each hot zone and in a solid mass through a heat transfer zone at a relatively slow rate, and withdrawing the solid carbonized combustible residue.

5 13. A process for carbonizing and distilling solid carbonaceous material in an oven which consists in introducing the material to be treated, raising its temperature sufficiently 10 to undergo combustion when treated with an oxygen-carrying gas, causing the material to move in a loose state, to pass downwardly through a series of hot zones in restricted streams, maintaining combustion at each 15 zone, causing the gases evolved by combustion to pass through the material in a generally upward direction, causing the material to remain in a loose state and commingling the particles, and withdrawing the solid carbonized combustible residue.

20 14. A process for carbonizing and distilling solid carbonaceous material in an oven which consists in introducing the material to be treated, raising its temperature sufficiently 25 to undergo combustion when treated with an oxygen-carrying gas, causing the material to move continuously in a downward direction and alternately contracting and expanding the same causing the material to be divided 30 into streams during contraction to obtain a relatively higher velocity, maintaining the material at relatively high temperature during division, and then combining the streams after contraction in a manner to reduce the 35 velocity and obtain a reduction in temperature.

15 15. A process for carbonizing and distilling solid carbonaceous material in an oven which consists in introducing the material to be treated, raising its temperature sufficiently 40 to undergo combustion when treated with an oxygen-carrying gas, causing the material to move continuously in a downward direction, causing the material to be contracted, then 45 dividing the material while thus contracted into separate streams to obtain a relatively higher velocity, causing combustion to take place during said higher velocity, and then causing the streams to combine into a single 50 stream, to travel at a relatively lower velocity, and maintaining a higher temperature during division, by introduction of an oxygen-carrying gas.

55 16. A process for carbonizing and distilling solid carbonaceous material in an oven, which consists in filling the oven with said material in stages and igniting the material at each stage, causing the material to move 60 substantially continuously through the oven, alternately contracting and expanding the material during motion and causing it to move at relatively high velocity during contraction, applying an oxygen-carrying gas 65 during such contraction and high velocity

motion, and withdrawing the solid carbonized combustible residue through the oven.

17. A process for carbonizing and distilling solid carbonaceous material in an oven, which consists in filling the oven with said 70 material in stages and igniting the material at each stage, causing the material to move substantially continuously through the oven, alternately contracting and expanding the material during motion and causing it to move at relatively high velocity during contraction, applying an oxygen-carrying gas 75 during such contraction and high velocity motion, partly effecting the heating of the material to combustion temperature by upward passage of the heated gases of combustion, and utilizing the withdrawing action of the combustible residue as a means to control the feed of the material through the oven.

18. A process for carbonizing and distilling solid carbonaceous material in an oven, which consists in filling the oven with said material in stages and igniting the material at each stage, causing the material to move substantially continuously through the oven, 80 alternately horizontally contracting and expanding the material during motion and causing it to move at relatively high velocity during contraction, applying an oxygen-carrying gas 85 during such contraction and high velocity motion, and withdrawing the solid carbonized combustible residue through the oven.

19. A process for carbonizing and distilling solid carbonaceous material in an oven, which consists in filling the oven with said material in stages, igniting the material, causing motion of the material, alternately contracting and expanding the material during motion through the oven, and causing it to move at relatively high velocity and in thinner layers during contraction, applying an oxygen-carrying gas during such contraction and high velocity motion, and withdrawing solid carbonized combustible residue.

20. A process for carbonizing and distilling solid carbonaceous material in an oven, which consists in filling the oven with said material in stages and igniting the material at each stage, causing the material to move substantially continuously downwardly, alternately horizontally contracting and expanding the material during motion through the oven, and causing it to move more rapidly during contraction, introducing oxygen-carrying gas during contraction and more 110 rapid motion, and controlling downward motion by removal of the solid carbonized combustible residue.

21. A process for carbonizing and distilling soiled carbonaceous material in an oven, 115 which consists in partly filling the oven with the material to be processed, raising the temperature of the material sufficiently to undergo combustion when directly treated with an oxygen-containing gas, causing the material 120

130

to travel through the oven in relatively restricted streams at relatively high velocity, applying the oxygen-containing gas during such streaming and velocity, causing the streams to unite and move at a relatively lower velocity, withdrawing the solid carbonized combustible residue, and utilizing the withdrawing action as a means to control the downward feed of the material.
